UNITED STATES PATENT OFFICE.

WALTER HOHAGEN, OF CHARLOTTENBURG, GERMANY, ASSIGNOR TO SIEMENS-SCHUCKERT WERKE G. M. B. H., OF BERLIN, GERMANY, A CORPORATION OF GERMANY.

VALVELESS PUMP FOR CONVEYING GASES.

1,107,425.

Specification of Letters Patent. Patented Aug. 18, 1914.

Application filed March 26, 1912. Serial No. 686,291.

To all whom it may concern:

Be it known that I, WALTER HOHAGEN, a citizen of the German Empire, and residing at Charlottenburg, near Berlin, Germany, have invented certain new and useful Improvements in Valveless Pumps for Conveying Gases, of which the following is a specification.

My invention relates to valveless pumps for conveying gases, in which liquid for packing the movable parts is kept at a predetermined level above the delivery port. In valveless pumps which are frequently employed as gas-pumps and, particularly, as vacuum-pumps, precautions are taken for avoiding difficulties which may arise owing to large quantities of oil or other liquid which is an equivalent for the same purpose being employed for packing the moving parts.

A primary object of my invention is to provide improved means for obviating the difficulties referred to.

One illustrative embodiment of my invention is represented by way of example in the accompanying drawing in vertical sectional elevation.

Referring to the drawing, the valveless pump shown is in itself of known form and comprises a casing α containing a cylinder c eccentrically journaled therein; the cylinder is provided with blades f , f , which when the cylinder rotates are driven radially outward and inward by the wall of the casing and thus connect the suction inlet s and the delivery port d with chambers of variable magnitude for producing the pumping effect. Valves are not required in such a pump. For the following reasons, however, a delivery valve has nevertheless frequently been employed. Namely, above the port d oil or an equivalent liquid has been kept at a considerable level in the chamber r formed like an air-vessel, in order that this oil or other liquid can constantly lubricate all the moving parts over which it can spread when the inner parts rotate, as clearly shown. In consequence of the oil entering into the interior of the pump from the delivery port and issuing with the conveyed gases through the same port considerable foam is produced and a number of small gas-bubbles in the oil, and if provision be not made that only oil as free from foam as possible can pass back into the

pump high degrees of vacuum cannot be obtained, because microscopic gas-bubbles will always pass between the rubbing surfaces into the suction chamber. In order to render the oil free from foam it has heretofore been proposed to provide in the chamber r above the delivery port a small ante-chamber containing a non-return valve through which the conveyed gas and the foamy oil issue, while the clear oil which gradually settles in the outer chamber r passes back through fine holes in the bottom of the ante-chamber into the pump. Now I have found that the oil can be rendered free from foam more simply and certainly in the manner which will now be described.

The delivery port d is closed by the plate ρ having only a few fine holes o , and the conveyed gas and the oil mechanically carried along with it pass at a relatively high velocity in the form of jets into the chamber r . The favorable action which is actually obtained in practice with this simple arrangement may be due to the foamy oil mechanically carried along being removed to a considerable distance from the port on account of the considerable velocity, so that the vigorous circulation of the oil thereby caused above the port causing only clear oil to pass back through the port, while the oil thrown to a distance has time to become free from foam before being circulated afresh.

It will be readily understood that the described end can also be attained by making the delivery port d itself sufficiently narrow in order to obtain the requisite velocity of the issuing gases. On account of the small changes and owing to a short port being advantageous for other reasons, the constriction by a plate or the like will, however, in general be preferred. The kind and position of the small holes will depend entirely on the circumstances of each case. When the motion of the particles of oil issuing at a high velocity is not impeded too early the intended action can be obtained by screwing on the plate only loosely. In other cases favorable results will be obtained, say, by means of small tubes or other forms of the small delivery orifices.

An essential feature of my invention is that the orifices or holes always have such a section and such a form and position that the mixture of gas and oil issues in the form

of jets in order as far as possible to allow only oil free from foam to pass into the pump.

It is to be understood that my invention is not limited to the pump described and shown but may be applied to other kinds of valveless pumps.

I claim:

1. In a pump of the character described, the combination of a casing having a fluid suction port and a delivery port terminating in a plurality of small orifices, means in the casing for driving successive volumes of fluid through the said orifices, said means being adapted to continuously decrease the volume of the space between it and said orifices, and means for submerging said orifices in a liquid, said volume decreasing driving means being adapted to drive a mixture of liquid and said fluid through said orifices in the form of jets.

2. In a pump of the character described, the combination with a casing having a suction port and a delivery port, means in the casing for sucking a gas through the suction port and driving it through the delivery port, while continuously decreasing the volume of the space below said delivery port, and a chamber for containing a liquid at a predetermined level above and in communication with the delivery port, of a perforated plate arranged between the said chamber and the delivery port, said suction and driving means being adapted to expel a mixture of liquid and gas in the form of jets through said perforated plate.

3. In a pump of the character described, the combination with a casing provided with

an inlet port and a delivery port terminating in a plurality of relatively small orifices, means for submerging said orifices in a liquid, and pumping means within said casing adapted to be packed by the liquid by which said orifices are submerged, said pumping means being adapted to continuously decrease the volume of the space between it and said orifices to drive a mixture of said liquid and gas from said casing in the form of jets issuing from said orifices whereby bubbles of said gas are prevented from vitiating the fluid packing of said pumping means.

4. In a pump of the character described, the combination with a casing having a suction port and a delivery port, a fluid chamber into which said delivery port discharges, means within said casing for pumping a gas in at the suction port and out at the delivery port, said means including a sliding member which is adapted to be packed by fluid from said fluid chamber, and a perforated plate interposed between said delivery port and fluid chamber, said pumping means being adapted to expel a mixture of gas and fluid from said casing in the form of jets issuing from the perforations in said plate, said gas being thereby prevented from collecting in bubbles within the casing where it vitiates the packing effects of said fluid.

In testimony whereof, I have signed my name to this specification in the presence of two witnesses.

WALTER HOHAGEN.
